[57] CLAIM

The ornamental design of a thermostat override housing, substantially as shown and described.

DESCRIPTION

FIG. 1 is a front elevational view of a thermostat override housing showing my new design, the rear being flat, plain and unornamented;

FIG. 2 is a left side elevational view thereof, the right side being a mirror image thereto;

FIG. 3 is a top plan view thereof;

FIG. 4 is a left front perspective view thereof.
